UNITED STATES PATENT OFFICE.

WILLIAM E. CHOATE, OF MELROSE, MASSACHUSETTS.

STENCIL UNIT.

1,084,315.

Specification of Letters Patent.

Patented Jan. 13, 1914.

Application filed December 7, 1907. Serial No. 405,509.

To all whom it may concern:

Be it known that I, WILLIAM E. CHOATE, a citizen of the United States, residing at Melrose, in the county of Middlesex, State 5 of Massachusetts, have invented an Improvement in Stencil Units, of which the following description, in connection with the accompanying drawings, is a specification, like letters on the drawings representing like parts.

This invention is applicable to printing forms and the like such, for example, as stencil units used for reduplicating addresses and indexes and for analogous purposes.

15 Ordinarily, stencil or other units of the character suggested, serve in addition to their duplicating office, as records or indices.

The invention consists of various features contributing to improve such units as regards all the uses to which they may be applied and which are defined in the annexed 20 claims.

Figure 1 is a plan view of a complete exemplary stencil unit; Fig. 2 is a detail section on the line 2—2 of Fig. 1; Fig. 3 is a detail perspective of a corner of the unit shown in Fig. 1; and, Fig. 4 is a plan view of the partially completed unit.

Fig. 1 of the drawings shows a completed stencil unit of convenient form in which the stencil characters are made in a sheet 10 of any suitable material such as paper, fabric, celluloid or the like. Preferably the sheet 10 has reinforcing means or 30 a frame 12 of a firmer material such for example as cardboard. The reinforcing means 12 may be formed by removing from a sheet of cardboard or the like a blank of the size of the desired opening to constitute a frame 35 (see 25, Figs. 2 and 4). Heretofore stencil sheets have been attached to their frames or other reinforcement by glue or cement; while in the instance shown in Fig. 1 the sheet 10 and illustrative frame 12 are secured together by metallic fastening means 40 consisting of strips 16, 17, 18 and 19. Said strips as shown are separate from each other and comprise pieces of metal folded over the edges of the assembled sheet 10 and frame 45 12, as shown on an enlarged scale in Fig. 2. If the oppositely disposed wings of the strips 16, 17, etc., are sufficiently pressed together they may suffice to fasten the sheet and frame 12 firmly together without necessitating any other fastening means, such 50 as an adhesive. If desired, one or more of

the strips 16, 17, etc., may be provided with spurs 20 arranged to project into and firmly engage the sheet and frame. The strips 16, 17, etc., may have their ends turned inwardly to supply spurs 21, as shown in Fig. 3.

For purposes of convenience and economy in manufacture it is preferred that the strips be separate. Preferably they extend along the respective edges of the unit and they may overlap at their edges or may have meshing parts of any suitable design, in order to add to the general stiffness of the finished unit.

In Fig. 4 a sheet 10 and reinforcing means 12 are combined with strips 22, 22 having an interlocking or intermeshed construction at the corners of the card. This arrangement and the overlapping arrangement at the corners in Figs. 1 and 2, supply stiffening means at each corner such that the unit can not be bent along a diagonal or the like, on a line which will not pass through part of the stiffening means with the resulting resistance to bending or breaking the card. At the same time the maximum thickness of the unit may be maintained uniformly having equal thickness of metal at all points.

In Figs. 2 and 3 the blank 25 (i. e., the part to be removed from the reinforcing or frame material to leave the opening) remains in position within the frame. With such an arrangement the reinforcing material, comprising the reinforce proper and the blank 25, presents a flat surface on one face of the unit and the stencil sheet on the other face, the two being secured together by the strips as already suggested. This construction supplies a very convenient form 95 for use with marking, punching or printing instrumentalities of any practicable sort; and for this purpose the blank 25 of reinforcing material may serve as a platen or cutting bed, if desired. For example, if the device shown in Fig. 4 be placed with its record sheet uppermost, and printing, stamping, stenciling, cutting or other tools be pressed thereupon firmly enough, an impression, perforation, or other demarcation 100 will be made upon the record sheet and may also be communicated through the latter to the adjacent face of the blank. In this manner two records may be duplicates, one serving conveniently for cross reference purposes or the like. Another method of utilizing such forms as are shown in Fig. 4 is to

place them in a stack of two or more, with their record sheets down. If the died out blank of the topmost in the stack be removed the record sheet will be exposed thereby to receive the action of proper stencil cutting or other tools and the opposed platen or cutting bed will be supplied by the died out blank of the frame next beneath.

When the record units are manipulated in the manner suggested to be printed or punched, they may receive rough usage; and, accordingly, it is desirable to employ the stiffening strips to reinforce the units against wear and preserve them in good condition. This is especially true in connection with automatic stencil cutting machines, to which units may be fed automatically to operative relation with the stencil cutting tools; and also with addressing machines in which the stencil units may be used. An arrangement of fastening strips 16, 17 etc. such as is shown in Fig. 1; and also a construction including the strips 22, 22 of Fig. 4, gives a strong, substantially rigid unit which may be fed accurately into a machine and during its feeding it may be protected from contact with any part except through the medium of its metallic rims.

It will be observed in Fig. 1 that each unit may have an index holder 30 which, for convenience, may be formed integral with a strip 16 or the like. The index holder 30 may have any convenient form to receive a removable index slip or the like; or it may itself be appropriately lettered. It will be observed that any break in the edge of fastening strips 16, 17, 18, 19 or 22, as, for example, by turning up the index holder 30, or removing a portion of strip 22 to form a display opening 32, will expose a part of the reinforcing material 12, its edge for instance, which may serve for indexing or distinguishing purposes. This feature may be utilized readily by employing for different groups of stencil units or index cards or the like, distinctive colors of reinforcing material displayed at openings, such as the opening 32 (Fig. 4). Assume a group of stencil units for use in an addressing machine for addressing a periodical publication. The entire group of stencil units may be separated into subdivisions determined by the date of expiration of subscriptions. Thus one group might consist of the address stencils of subscriptions expiring in January. Another group of those expiring in February, and so on. Each such group might have reinforcing or frame material of a color distinctive from the other groups, this color being displayed in any practicable manner, as for example through the opening supplied by bending up an index holder 30 or by notching or otherwise breaking the continuity of the strip 22 or its substitute. In like manner different combinations of

colors may be used in different stencil units or the like, as by having two or more different colored layers of reinforcing or frame material; all such arrangements as have been suggested are susceptible of use with 70 stencil or other record units, such as are shown for illustration in the drawings.

Any suitable number of display openings 32, or their equivalents may be employed on a single unit; and their numbers or positions 75 may serve to indicate some characteristic pertaining to the unit or may serve to distinguish from other units. These suggested indexing or distinguishing means are capable of wide variation and are applicable 80 conveniently to many different uses.

The specific article above described may be made readily by a method embodying features of this invention as, for example, a method comprising the following steps: 85 Assembling the record sheet and the reinforcing material, as for a frame, while the latter is in condition to supply a platen or cutting bed; next, additionally protecting the assembled sheet and reinforce material 90 by means which may serve also for fastening them together; next making the desired record upon the record sheet in such a manner as to have the record communicated to the reinforcing material; and thereafter removing superfluous reinforcing material 95 with a duplicate record thereon.

The brief discussion in the preceding paragraph will serve to illustrate the character of the method contemplated by this 100 invention; but it is not essential that the steps of the method be performed in the exact sequence suggested nor, perhaps, are all the steps necessary.

This invention is applicable to many uses 105 unnecessary to be mentioned herein and is also susceptible of embodiment in a variety of forms and methods. No attempt has been made heretofore to indicate the scope of the invention, this office being delegated exclusively to the subjoined claims.

Claims:

1. An article of manufacture comprising a sheet to receive a record; reinforcing material connected thereto; and protecting 115 means at the edges thereof, said reinforcing material including a blank positioned to serve as a platen or cutting bed to oppose the operation of making the record on the sheet.

2. An article of manufacture comprising a record receiving sheet; a reinforcing frame for said sheet; and platen means removably fitting within said frame against said sheet 125 for receiving the record of said sheet.

3. An article of manufacture comprising a record receiving sheet 10; a reinforcing frame 12 superposed thereon and containing a blank 25 serving as a platen or cutting bed; and metallic edge binding means 16, 130

17, 18, 19 embracing superposed portions of said record sheet and reinforcing frame.

4. An article of manufacture comprising a sheet to receive a record, reinforcing material connected thereto, and including a sheet facing the record sheet, a bounding strip inclosing and in the plane of said facing sheet, and protecting means engaging and uniting said record sheet and bounding strip.

5. An article of manufacture comprising a record receiving sheet; cutting bed or

platen means for receiving the record of said sheet; and reinforcing means having provision for detachably connecting said sheet and platen means in superposed relation.

In testimony whereof, I have signed my name to this specification, in the presence of two subscribing witnesses.
